UNITED STATES PATENT OFFICE.

ALLEN H. KERNGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

LEVER BELT BUCKLE.

Application filed June 20, 1922. Serial No. 569,679.

To all whom it may concern:

Be it known that I, ALLEN H. KERNGOOD, a citizen of the United States, residing at Baltimore, in the State of Maryland, have 5 invented a certain new and useful Improvement in Lever Belt Buckles, of which the following is a full, clear, and exact description.

The object of this invention is to provide 10 a belt buckle in which one end of the belt is clamped in a pivotally mounted lever clamping member and the other end is adjustably secured by the action of this clamping member upon another clamping member.

15 The invention consists of a lever belt buckle, in which there is a frame in which a lever clamping member is pivotally mounted and between which lever clamping member and the adjustable end of the belt is 20 interposed a floating clamping member movable by the lever clamping member to clamp and release the adjustable end of the belt, as I will proceed now to explain and finally claim.

25 In the accompanying drawings illustrating the invention, in the several figures of which like parts are similarly designated, Figure 1 is an outside plan or face view of the buckle applied to a belt. Fig. 2 is a side elevation. Fig. 3 is an inverted plan view. Fig. 4 is a longitudinal section on line 4-4 of Fig. 3, of the buckle alone in the clamping position. Fig. 5 is a longitudinal section of the buckle alone with the parts in releasing 35 position. Fig. 6 is a perspective view of the base or frame of the lever clamping member. Fig. 7 is a perspective view of the floating clamping member. Fig. 8 is a side elevation illustrating a modification.

40 The frame 1 of the buckle may be of any approved construction, same being shown as composed of a face plate 2, having parallel rearwardly extending side flanges 3, and at one end these side flanges may have the re- 45 entrant portions 4, if desired.

The lever clamping member herein referred to, comprises a substantially flat base piece 5, having parallel offstanding ears 6, and the inclined extension 7, terminating in an abruptly turned lip 8, and pivot lugs 9, these last being arranged in holes 10 in the side flanges 3 of the frame, so that the lever clamping member has a pivotal movement in the frame. The ears 6 have holes 11 in

which are pivoted the belt-clamping lever 12, 55 of any suitable construction, herein shown as a finger-piece 13 having a toothed or otherwise formed down-turned edge 14 which engages the belt between itself and the base piece 5. This belt clamping lever has the lugs or 60 trunnions 15 mounted in the holes 11 in the ears 6. Any other suitable means than the lever 12 may be used to fasten one end of the belt to the lever clamping member.

The side flanges 3 are provided with the 65 arcuate slots 16 on opposite sides, and in these slots are arranged the lugs or trunnions 17 of a substantially cylindrical floating clamping member 18, which is open at the top, as shown at 19, to receive the lip 8 70 of the lever clamping member, so that by movement of the lever clamping member on its pivots 9 as an axis this clamping member 18 will be moved back and forth in the slots 16 so as to approach toward or recede from the back of the face plate 2 of the frame with the adjustable end of the belt interposed between the two, and then by appropriate movement of the lever clamping member the floating clamping 75 member will be moved so as to engage or release the adjustable end of the belt.

Instead of using the arcuate slots 16, they may be replaced by arcuate housings 20, as shown in Fig. 8. The arcuate slots and 85 their alternatives, the arcuate housings, may be designated functionally as guideways.

The arcuate guideways are eccentric with respect to the pivotal axis of the lever clamping member and they extend in opposite directions from a plane passing through the pivotal axis aforesaid and normal to the face plate. These guideways therefore are to a greater or less extent arranged between the pivotal axis and the face plate, that is 90 to say, relatively in front of the pivotal axis of the lever clamping member. As the floating clamping member rides or travels back and forth in these guideways under impulse of the lever clamping member, it 95 rocks upon its lugs or trunnions 17 in following the curvature of the guideways.

As will be seen, the lever clamping member and the floating clamping member are 100 separately and independently mounted in the frame, while the movement of the floating clamping member is controlled by the lever clamping member, to the extent of

shifting it back and forth in its arcuate slots in the sides of the frame. It is to be noted, however, that the lip 8 of the lever clamping member does not act as a cam to depress the floating member into clamping action on the strap. The primary function of this lip is to assist or guide the floating clamping member in its necessary movements to engage the strap.

10 By the construction shown not only is a very simple and effective buckle produced, but the lever clamping member is incapable of turning over backward and thus causing the user annoyance and difficulty in operating it. As indicated in Figure 5, the lever clamping member stands up substantially at right angles to the frame of the buckle when in the open position and is held in this position by the lugs or trunnions of the floating 15 clamping member coming to rest in and being stopped by the upper ends of the slots 16 or their equivalents, the housing 20. The inclined extension 7 throws the lip 8 so far forward that when the lever clamping member is raised to release or receive a belt end to be clamped by the floating clamping member, said lever clamping member does not go over backward, and it is not necessary to manipulate the buckle as a whole in 20 order to effect these operations.

In order to increase the bite of the floating clamping member on the belt, it may be longitudinally milled or otherwise roughened as indicated at 21 in Figs. 3, 4, 5 and 7.

35 While I have shown and described the invention as embodied in a belt buckle, it is to be understood, of course, that the invention is applicable to buckles for other purposes, and the claims herein are to be understood accordingly.

40 As already indicated, the invention is susceptible of structural variations and these and others are permissible within the spirit and scope of the invention and the claims hereinafter made.

45 What I claim is:—

1. A lever belt buckle, having a frame provided with sides having arcuate guideways, a lever clamping member pivotally mounted in said frame, and a floating clamping member arranged to be moved back and forth in said guideways in the frame and operatively connected with the lever clamping member.

55 2. A lever belt buckle, having a frame provided with sides having arcuate guideways, a lever clamping member pivotally mounted in said frame and having a depending lip arranged in advance of its pivotal axis, and a floating clamping member having a defined path of movement in the arcuate guideways and engaged by the said depending lip.

60 3. A lever belt buckle, having a frame provided with sides having arcuate guide-

ways, a lever clamping member pivotally mounted in said frame and having a depending lip arranged in advance of its pivotal axis, and a floating clamping member having a defined path of movement in 70 said arcuate guideways and in constant engagement with said depending lip.

4. A lever belt buckle, having a frame including a face plate, a lever clamping member pivotally mounted in said frame 75 and having a depending lip arranged in advance of its pivotal axis, said lever clamping member adapted to engage one end of a belt, and a substantially cylindrical floating member, said frame having side flanges 80 provided with arcuate guideways arranged in front of the pivotal axis of the lever clamping member, and said floating member engaged by said depending lip and movable with the lever clamping member beyond a 85 plane passing through the pivotal axis of said lever clamping member and normal to its face plate.

5. A lever belt buckle, having a frame including a face plate, a lever clamping member pivotally mounted in said frame and having a depending lip arranged in advance of its pivotal axis, said lever clamping member adapted to engage one end of a belt, and a substantially cylindrical floating member, 90 said frame having side flanges provided with arcuate guideways arranged in front of the pivotal axis of the lever clamping member and engaged by said depending lip and movable with the lever clamping member beyond a pivotal plane of said lever clamping member normal to the face plate 95 and to opposite sides of said plane.

6. A lever belt buckle, having a frame provided with side flanges having arcuate 100 guideways, a lever clamping member pivotally mounted in said side flanges and having a base plate provided with an inclined portion slanting toward the front of the buckle, said inclined portion having the 105 pivots which engage the side flanges, and said inclined portion also having an abruptly turned terminal lip which also extends toward the front of the buckle, and a floating clamping member engaged by said terminal flange and arranged in said guideways 110 in the side flanges, said guideways located between the lever clamping member and the front of the buckle and extending on both sides of a pivotal plane of the lever clamping member normal to the front.

7. A lever belt buckle, having a frame, a lever clamping member pivotally mounted in said frame, and a substantially cylindrical floating clamping member operatively connected with the lever clamping member and bodily movable in both directions beyond a pivotal plane of the lever clamping member which is normal to the front of the buckle and also having a 115 120 125 130

limited rocking movement under the operation of the lever clamping member.

8. A lever belt buckle, having a frame provided with side flanges, a lever clamping member pivotally mounted in said side flanges, and a floating clamping member, said side flanges having arcuate guideways in which the opposite ends of said floating clamping member are arranged and in which

10 said floating clamping member has a sliding movement.

9. A lever belt buckle, having a frame provided with side flanges, a lever clamping member pivotally mounted in said side

15 flanges and a floating clamping member, said

side flanges having arcuate guideways extending on opposite sides of the pivotal plane of the lever clamping member normal to the front and in which guideways opposite ends of the floating clamping member are arranged, said lever clamping member and floating clamping member being operatively connected.

In testimony whereof I have hereunto set my hand this nineteenth day of June, A. D. 1922.

ALLEN H. KERNGOOD.
